UNITED STATES PATENT OFFICE

CHARLES W. MCKINLEY, OF FLINT, MICHIGAN, ASSIGNOR TO A C SPARK PLUG COMPANY, OF FLINT, MICHIGAN, A COMPANY OF MICHIGAN

OIL FILTER

Application filed November 29, 1929. Serial No. 410,376.

This invention relates to oil filters and has particular reference to an oil filter of the spiral bag type and the mounting thereof in its container.

The oil filter container is composed of separable parts in order that access may be had to the filtering material to remove and replace it. The filtering element of the invention is mounted in the container as a unit and 10 comprises a spiral wire over which a filter bag is placed. A wire or cord is wound between the spiral of the wire and entwines or pulls the filter bag into the spirals to thereby give a spiral-formed filtering unit. End 15 plates are at each end of the filter unit, one of the plates being rigidly secured to the filter bag by means of an outlet nipple. The other end plate is freely placed on the bag and is joined to the first end plate by means 20 of a plurality of straps having flanges facing outwardly of the filter. Both ends of the straps are hooked into openings in the end plates and adjacent one of the plates, preferably the plate rigidly secured to the filter 25 bag, the flanges on the straps are cut away in order to permit of a limited movement between the straps and end plate. The purpose 30 of this movement is to utilize the spring tension to hold the nipple tightly on its seat as well as to keep the bag assembly unit tightly in its shell, the movement being limited so as to thereby prevent the nipple from coming out of its seat or socket during shipping in transit or while applied to a vehicle.

35 On the drawings:

Figure 1 is a sectional view through the filter showing portions of the filter bag in section and in elevation.

40 Figure 2 is a side elevation of the filter container.

Figure 3 is a plan view of the structure of Figure 2 on a reduced scale.

Figure 4 is a side view of the structure of 45 Figure 2 on a reduced scale.

Figure 5 is a view of the spiral wire filter bag and end plate showing a portion of the bag entwined in the spiral wire and the remaining or lower portion free.

50 Figure 6 is a view of the filter bag per se.

Referring to the drawings, the numeral 2 indicates the container as a whole. The container comprises the upper separable portion 4 and the lower portion 6, each having a flange 8 and 10 at their place of meeting. 55 The flange 8 is also upwardly turned as indicated at 12 and a gasket 14 is received between the flanges to make an oil tight connection. A ring 16 is secured to the upper section 4 immediately adjacent the flange 10 and is provided with a plurality of openings to receive the bolts 18. The ring 16 preferably comprises the two right angularly bent flange portions 20 and 22, the flange portion 20 striking against the flange 10 60 of the portion 4 of the container.

The lower portion 6 of the container 2 is also provided with a ring 19 comprising the flange portions 20 and 22, the portion 20 of which strikes against and supports the flange 8 of the container. The ring 16 is preferably loosely mounted on the container but may be rigidly mounted if desired and is provided with openings adapted to receive the bolts 18. The openings in the rings 16 and 19 of course conform to each other. Nuts 24 are applied to the bolts to pull the two halves on to each other and to tighten the rings 16 and 19 and flanges 8 and 10 on the gasket 14. By unscrewing the screws 24, 75 the upper half 4 may be removed from the lower half 6.

The lower ring 19 is provided with an integral bracket portion 26 having the openings 28 for the reception of bolts to secure 85 the filter to a suitable mounting. The lower half 6 is also provided with the ring clamp 30 having its ends secured together by means of the bolt and nut 32. The ends 34 are provided with the openings 36 to serve as an additional means to secure the filter in place. The clamp ring 30 may, if desired, be entirely omitted.

The bottom 37 of the lower portion 6 of the container is provided with the fitting or socket 38 adapted to receive the screw-threaded plug 40 which serves as a drain.

A fitting or socket 42 is also mounted at the bottom of the container and is screw- 100

threaded for the purpose of receiving the inlet pipe to the filter.

A third fitting or socket member 44 is rigidly mounted in the container bottom and 5 has the screw-threaded bore or opening 46 to which the outlet pipe is adapted to be attached. The inner portion of the socket 44 is rounded as at 48 and adapted to receive the corresponding rounded portion 50 of the 10 nipple 52 which is provided with a bore 54 communicating with the outlet pipe of the filter.

The filtering unit of the invention is indicated as a whole at 56 and is adapted to be 15 inserted and removed as a unit from the container 2. The filtering unit comprises the relatively heavy resilient spiral wire 58 over which there is drawn the filter bag 60 as is best shown in Figures 1 and 5. The filter 20 bag comprises a relatively long substantially cylindrical bag of preferably cotton and preferably has its nap facing outwardly. An end plate 62 is rigidly and permanently secured to the bag 60 by means of the nipple 25 52 as is shown in Figures 1 and 5, and after the nipple has been fastened to the plate and bag, a wire or string 64 is passed through and secured in an opening 66 in the plate 62 and wound around the bag and spring spiral 30 58 between the windings thereof as shown at the upper portion of Figure 5, to pull the cloth into the spirals and cause the filter bag to be entwined or enmeshed with the spiral. The manner of accomplishing this is illustrated 35 in Figure 5 in which the lower portion of the bag is shown in its original form and not wound with the spirals of the spring.

A second end plate 68 is placed over the 40 opposite end of the spiral wire 58 but is not secured to the bag or spiral. If desired, a cloth disc may be placed between both of the end plates and the filter bag 60.

Both end plates 62 and 68 are provided with openings 70 adapted to receive the 45 hooked ends 72 of straps 74 which have the lateral flanges indicated at 76. Adjacent the upper plate 68 the flanges 76 preferably are arranged very close to the plate to permit very little if any movement. At the lower 50 end, the flanges 76 are cut away as shown at 78, the purpose of which is to allow a limited amount of movement of the plates toward and from each other. The purpose of this 55 limited movement is to utilize the tension of the spring or spiral wire 58 to hold the nipple 52 tightly on its seat 48 in the socket 44 as well as to keep the bag assembly unit 56 tightly in its shell or container 2 and by the limited movement to prevent the nipple 52 from coming 60 out of the seat 48 during shipping or as a result of rattling when the filter is applied, as for instance to an automotive vehicle.

By referring to Figure 6, it will be noted 65 that the filter bag 60 comprises a long strip of filtering material folded upon itself as at

80 and sewn as at 82 entirely along one side. The end 84 is also sewed and a seam is formed half-way down the other side as shown at 86. With the bag in this form, the end plate 68 and nipple 58 are applied and the three rigidly secured together. The spring or spiral wire 58 is then inserted at the open portion 88 and the bag is sewed along the open portion 88. The wire or spring 64 is then applied in the opening 66 and wound between the spirals of the spring 58 to draw the bag between the spirals as is shown at the upper portion of Figure 5 and in Figure 1. The end plate 68 is then applied and the straps 74 secured in place. The unit 56 is then complete and may be inserted in the container 2 so that the nipple 52 will fit in the seat 48. The upper portion 4 of the container is then applied and the bolts 18 and nuts 24 secured in place to rigidly hold the filter in the container. 75 80 85

In operation the oil enters at the inlet 42 and passes between the spirals of the filtering material. The cloth will retain the impurities while the filtered oil will pass through the interior of the filter and out through the nipple 52 and socket 44 to the outlet pipe. When it is desired to clean the filter, the cover 4 is removed and the unit 56 withdrawn as a whole. It may be cleaned 90 in any suitable way and then replaced or a new filter unit may be applied. 95

If desired, the oil may be caused to enter the filter at the socket 44 and pass outwardly through the cloth and leave at the socket 42. 100 In the case of this reversed flow, the sludge or impurities will of course be collected on the inside instead of the outside of the bag. 105

I claim:

1. In an oil filter, a container, a filtering medium mounted in said container, end plates over said medium, means pressing said plates apart, a plurality of flanged straps connecting said end plates to confine said medium, and cut-away portions on said flanges at one 110 of said plates to permit a limited movement of said plate longitudinally of said straps. 115

2. In an oil filter, a container, a filtering medium mounted in said container, end plates over said medium, means for pressing said plates apart, a plurality of straps, hooks on said straps engaging said plates to retain said medium, and flanges on said straps having cut-away portions to permit limited longitudinal movement between one of said plates 120 and said straps. 125

3. In an oil filter, a separable container, a filtering unit removably mounted in said container and comprising a spiral wire, a filter bag over said spiral and entwined therewith, end plates, one of which is freely positioned on said bag, means interconnecting said plates at their edges to confine said bag and wire, a bored oil flow nipple securing the other of said plates to said bag, and a 130

hollow oil flow socket in said container adapted slidably to receive and position said nipple.

4. In an oil filter, a container, a filtering unit for insertion in said container, said unit comprising an end plate having an oil flow opening, an impervious second end plate, means between said plates to press said plates apart, said unit having an unobstructed mid portion, a filtering medium over said means, said second plate freely positioned on said means and medium and abutting against the container end, and means exterior to said filtering medium for holding said plates and permitting a limited movement of one of them longitudinally of said means.

In testimony whereof I affix my signature.

CHARLES W. McKINLEY.
